UNITED STATES PATENT OFFICE

107,981

DESIGN FOR A DISPLAY CONTAINER FOR WATCHES

Samuel Weissman, New York, N. Y.

Application May 4, 1937, Serial No. 69,146

Term of patent 7 years

To all whom it may concern:

Be it known that I, Samuel Weissman, a citizen of the United States, residing in the Borough of Manhattan, city, county, and State of New York, have invented a new, original, and ornamental Design for a Display Container for Watches, of which the following is a specification, reference being had to the accompanying drawing, forming a part thereof.

Fig. 1 is a perspective view of the display container, showing the rear cover in lowered or open position;

Fig. 2 is a front elevation of the display container showing the rear cover in closed position, and

Fig. 3 is a side elevation thereof.

I claim:

The ornamental design for a display container for watches as shown.

SAMUEL WEISSMAN.
